UNITED STATES PATENT OFFICE.

RICHARD DE SOLDENHOFF, OF 71 ST. MARY STREET, CARDIFF, COUNTY OF GLAMORGAN, ENGLAND.

FURNACE FOR THE DESICCATION, INCINERATION, AND CARBONIZATION OF PRECIPITANTS, &c., RESULTING FROM SLUDGE, &c.

SPECIFICATION forming part of Letters Patent No. 409,022, dated August 13, 1889.

Application filed September 26, 1887. Serial No. 250,736. (No model.) Patented in England February 24, 1886, No. 2,721.

To all whom it may concern.

Be it known that I, RICHARD DE SOLDENHOFF, engineer, a subject of the Queen of Great Britain, residing at 71 St. Mary Street, 5 Cardiff, in the county of Glamorgan, England, have invented certain new and useful Improvements in Furnaces for the Desiccation, Incineration, and Carbonization of Precipitants or Solids Resulting from Sludge or 10 other Substances Liable to Putrefy, (for which I have received Letters Patent in Great Britain, No. 2,721, dated February 24, 1886,) of which the following is a specification.

The above-named substances are to be desiccated, carbonized, and incinerated by the heat developed by the consumption of their own combustible compounds—such as carbon, hydrogen, phosphorus, and sulphur—in furnaces, as herein described.

20 In the accompanying drawings, Figure 1 is a cross-section, looking toward the front, of a group of furnaces constructed according to my invention, taken on the line *y y*, Fig. 2. Fig. 2 is a horizontal section thereof, looking 25 downward, taken on the lines *E* and *E'* *F* of Fig. 1. Fig. 3 is a longitudinal section on the lines *A* *B* of Fig. 1. Fig. 4 is a similar section on the line *C* *D* of Fig. 1, and Figs. 5 and 6 are detail views of parts of the floor of the 30 bottom flue.

Throughout the drawings the featherless arrows indicate the course of the air before it comes in contact with the gases from the burning refuse, and the feathered arrows indicate the course of the gases emanating from 35 said burning refuse.

The furnaces are to be built always in pairs—that is to say, the least number to be used is two furnaces—situated side by side; but any 40 even number of furnaces may be employed. Each furnace is composed of two chambers—an upper one *A* and a lower one *B*.

The upper chamber *A* is the desiccating or 45 drying chamber, while the lower chamber *B* is the incinerating or carbonizing chamber. The upper chamber *A* is provided with one, two, or more openings *a* in the top, through which the said chamber is to be charged with the material to be desiccated, and with one

or more end openings. When one of the 50 openings *b* is employed, it is placed in front, while at the back is a permanent closure, and when two openings are employed one opening is placed in the front end and the other opening *b'* in the back end thereof. Each of these end 55 openings is large enough to permit a rabble to be passed through it, so as to level the material in the said upper chamber *A*. The openings in the top are closed by means of cast-iron covers *a'*, while those in the ends 60 are closed by means of doors, as hereinafter described. Each of these upper chambers *A* is situated above a lower chamber *B*, and is put in connection with it by three openings 65 *c*, situated immediately underneath the charging-openings *a*. These openings *c* are closed with fire-brick covers *c'*, provided with wrought-iron handles, by which they may be taken out through the charging-openings *a*.

The openings *c* are for the purpose of enabling the material when sufficiently dry to be passed through them from the upper chamber *A* into the lower chamber *B*. The lower chamber *B* is provided with doors *B'*, as hereinafter described. 75

Each pair of lower chambers *B* is situated above and parallel with six horizontal flues *C* *D* *E* *C'* *D'* *E'*, the flues *C* *D* *E* being arranged in a tier one above the other under one chamber *B*, and the others *C'* *D'* *E'* arranged likewise and parallel with the flues *C* *D* *E* under the other chamber *B*, the arches or crowns of the flues *C* and *C'* constituting the floors of the chambers *B*. The floor of the top flue may be horizontal, as shown, or 85 slightly inclined from the center to both ends; or it may be inclined from the back to the front. The top flues *C* and *C'* and bottom flues *E* and *E'* are gas-flues. The intermediate, flues *D* *D'* are air-regenerative flues, which 90 two latter, as fully shown in Figs. 2, 3, and 4, have a great number of communicating ports or passages *D*⁵. Each side wall of the upper chamber *A* of the furnace is formed with a horizontal air-flue *F*, which is in connection with another horizontal flue *G*, formed in the side walls of the lower chambers *B* directly 95 below the flues *F*, through a series of open-

ings *d* in the roof of said flue *G*. The flues *F* and *G* communicate with the oven-chamber *B* by openings *e* and *f*, the said openings *e* and *f* being alike, as plainly shown at Figs. 3 and 4. From the flue *G* to the floor of the flue *C* there are shown twenty-eight vertical flues *H*; but any other number of such flues may be employed. These are repeated in every side wall except the last on the right-hand side and the last on the left-hand side. At these latter places two horizontal flues divided by a floor *g* are employed instead, the flue above said floor being in communication with the chamber *B* through the ports *e f*, while the flue below communicates at one end with the flue above, and at the opposite end with flue *C* or *C'*, thus causing the gas to traverse the full extent of both flues above and below the floor before entering the flue *C* or *C'*. These vertical flues *H* are gas-flues, which convey the products of combustion to the ports *C²* in the side of each flue *C*, whence such products enter the latter. Thus the gases from the two chambers in each furnace are caused to meet in the flue *C*, and after traversing together the greater portion thereof pass into the next flue *C'* *via* the transverse end flue *X*. (See Figs. 3 and 4.) From these flues *C* and *C'* the gases pass through vertical flues *p p'* into the bottom flues *E E'*, and from there into the main flue *J*. (See Figs. 3 and 4.)

The first flue *D* on the left-hand side receives the cold air through the flue *D³*, which, after traversing through all of the flues *D*, passes, *via* ports *D⁴*, into vertical flues *K K'*, which latter lead directly to transverse horizontal flues *N*, each having vertical openings or flues *r r'* on opposite sides of their partitions *r³* in their bottoms leading to the air-flues *F* for conveying the air to the latter, from whence it enters the lower air-flues *G* through the openings *d*, or into the ovens or chambers *B* through openings *e* and *f*. The flues *F* are provided with continuations *r⁴* of the partitions *r³*, which divide such flues *F* into three chambers, as shown in Fig. 4. These partitions *r³*, with their lower extensions *r⁴*, are for the purpose of splitting the current of air passing along the flues *N*, and more equally dividing the volume in the flues *F*.

In some cases, if necessary, the gases would be passed intermittently into two Siemens' regenerators situated in the main flue between the ovens and the chimney, so that the waste gases would traverse the regenerators before passing to the chimney, and the air passing into them intermittently would pass through one of the regenerators at a time before entering the vertical flues *K K'*.

The working of the furnace is as follows: The furnace being first suitably heated by coke or other fires, the material to be treated is charged first into the upper chamber *A* of the furnace to dry, from whence, after the moisture is expelled, it is dropped into the

lower chamber *B*. In this lower chamber *B*, the material operated on, owing to the heat of the side walls and floors and owing to the presence of hot air delivered by the upper air-flue *F*, will inflame and expel the gases. The gases, partly burned in the oven and partly in the flue, will produce heat and render it to the side walls. The waste gases and the heat will, after having escaped from the ovens, pass into the lower air-flue *G*, in which they will mingle with the gases of the next oven, and also with the hot air passing to the lower air-flue *G* through the openings *d* in the floor of the upper air-flue. Therefore all the gases not yet inflamed in the furnace will become ignited in this lower air-flue *G*. The products of combustion will then find their way through the vertical flues *H*, by which they will be conducted to the flue *C* *via* their side ports *C²* under the floors of the ovens or chambers *B*, and in which flue *C* the gases traveling in two side walls, both belonging to the same furnace, but each used by gases of two furnaces, mingle together. A small part of the gases in this flue *C*, in which they meet, will be taken off by the flue *p* at the end of the flue *E*, while the bulk of the gases in the flue *C* will flow into the flue *C'* *via* the flue *X*, whence, by the vertical flue *p'*, they will pass into the flue *E'*. (See Fig. 4.) The object in allowing a portion of the combined gases in flues *C C'* to escape through flues *p p'* is to heat the flues *D D'*, and this will naturally be the result, as the gases passing in the flues *C C'* heat the upper parts of the flues *D D'*, while the gases passing in the flues *E E'* heat the bottoms of flues *D D'*, and the two latter being in communication they will of course share the heat. The cold air first enters the flue *D* and passes through similar flues from one end of the block of furnaces to the other, where, by the two vertical flues *K K'*, as stated above, it is led into the two flues *N N*, situated on the top of the furnaces. From these the hot air enters all the upper air-flues *F* through the openings *r r'*, whence it is distributed into the ovens and lower air-flues *G*, as described. When the material submitted to incineration in the chamber *B* of the furnace has expelled all its gases and been reduced to the state of ashes, the doors *B'* of the furnace are opened and the ashes are rabbled out by hand or by special machinery designed for that purpose. The doors of the furnace are made of wrought or cast iron, and lined with four or five inches of fire-brick. The perfect closure of furnaces is secured by luting them with clay from the outside. The doors are suspended on hinges or are lifting doors. In the latter case the top of the furnaces will be provided with crabs or other lifting means to lift the doors.

The moisture evaporating in the upper chamber *A* of the furnace will find its way through the middle charging-hole, which will be left open for that purpose, only in

case of wet weather the opening will be provided with a cover, so as to protect the inside of the chamber A from being wet.

The floor of the lower chamber B of the 5 furnace is not flat, but is curved; or it may have an undulated or serrated shape, as shown at Figs. 5 and 6, in order to develop the heating-surface of the floor.

The bricks in the side walls separating the 10 lower chamber B from the flues G and H are about three inches thick.

In case the Siemens regenerators, before referred to, were applied, the flues D and E would be suppressed, and the gases leaving 15 the flues C C' would be directed into the main flue, and from there by an arrangement, as described, diverted to the regenerators.

Having now particularly described and ascertained the nature of my said invention 20 and in what manner the same is to be performed, I declare that what I claim is—

1. A refuse-furnace having an upper chamber formed with charging-openings, the lower chamber, the charging-openings connecting 25 the chambers, the air-flue in the wall of the upper chamber, the gas-flue in the wall of the lower chamber, the openings connecting the air and gas flues, and the air and gas openings connecting the lower chamber with the 30 gas-flue, substantially as described.

2. A refuse-furnace having an upper chamber formed with charging-openings, the lower chamber, the charging-openings connecting the chambers, the air-flue in the wall of the 35 upper chamber, the gas-flue in the wall of the lower chamber, the openings connecting the air and gas flues, the air and gas openings connecting the lower chamber with the gas-flue, the vertical gas-flues, the top gas-flue, 40 the lower gas-flue, the intermediate air-flue, the vertical air-flues, the top air-flues, and the openings connecting the top air-flues with the air-flue in the wall of the upper chamber, substantially as described.

45 3. A refuse-furnace having an upper chamber formed with charging-openings, the lower chamber, the charging-openings connecting

the chambers, the air-flue in the wall of the upper chamber, the gas-flue in the wall of the lower chamber, the openings connecting the 50 air and gas flues, the air and gas openings connecting the lower chamber with the gas-flue, the vertical gas-flues, the top gas-flue, the lower gas-flue, the intermediate air-flue, the vertical air-flues, the top air-flues, the 55 openings connecting the top air-flues with the air-flue in the wall of the upper chamber, and the main flue, with which the lower gas-flue connects, substantially as described.

4. A refuse-furnace having upper chambers 60 A A, formed with charging-openings a, the lower chambers B B, the charging-openings c, connecting the upper and lower chambers, the horizontal air-flue F in the wall between the upper chambers, the horizontal gas-flue G and 65 vertical gas-flues H in the wall between the lower chambers, the openings d, connecting the horizontal air-flue with the horizontal gas-flue, and the openings e and f, connecting the lower chambers with the horizontal gas-flue, 70 substantially as described.

5. A refuse-furnace having the upper chambers A A, the lower chambers B B, the horizontal air-flue F in the wall between the upper chambers, the horizontal gas-flue G and 75 vertical gas-flues H in the wall between the lower chambers, the openings d, connecting the horizontal air-flue with the horizontal gas-flue, the openings e and f, connecting the lower chambers with the horizontal gas-flue, 80 the top flues C and C' beneath the lower chambers, the bottom flues E E', the intermediate air-flues D D' between the top and bottom gas-flues, the vertical air-flues K K', the top air-flues N, the openings r, connecting the 85 top air-flue with the horizontal air-flue, and the openings p p', connecting the top flues C C' with the bottom flues E E', and the main flue J, substantially as described.
